TYPEWRITING MACHINE,
APPLICATION FILED APR. 9, 1921.

Patented July 11, 1922.

2 SHEETS—SHEET 2.

UNITED STATES PATENT OFFICE.

JOSEPH PHELPS, OF NORTH CALDWELL, NEW JERSEY, ASSIGNOR TO REMINGTON TYPEWRITER COMPANY, OF ILLION, NEW YORK, A CORPORATION OF NEW YORK.

TYPEWRITING MACHINE.

1,422,617.

Specification of Letters Patent. Patented July 11, 1922.

Application filed April 9, 1921. Serial No. 459,902.

To all whom it may concern:

Be it known that I, JOSEPH PHELPS, citizen of the United States, and resident of North Caldwell, in the county of Essex and 5 State of New Jersey, have invented certain new and useful Improvements in Typewriting Machines, of which the following is a specification:

My present invention relates to ribbon 10 mechanism for writing machines and the chief object of said invention is to provide new and improved devices for reversing the ribbon feeding mechanism or so controlling it as to reverse the direction in which the 15 ribbon is fed. My invention is designed as an improvement on the ribbon reversing mechanism disclosed in the application of Edwin E. Barney, Sr., No. 456,907, filed March 30, 1921.

20 To the above and other ends which will hereinafter appear my present invention consists in the features of construction, combination of devices and arrangements of parts hereinafter described and particularly 25 pointed out in the claims.

In the accompanying drawings which illustrate the preferred form of my invention,

Fig. 1 is a fragmentary transverse vertical sectional view of parts of a typewriting machine embodying my invention.

Fig. 2 is a fragmentary vertical sectional view taken axially through one of the ribbon spools.

Fig. 3 is a horizontal sectional view taken 35 on a plane indicated by the dotted line 1—1 in Fig. 2 and looking downward in the direction of the arrow at said line.

Fig. 4 is a horizontal sectional view taken on planes indicated by the dotted line 2—2 40 in Fig. 2 and looking downward in the direction of the arrow at said line.

Fig. 5 is a horizontal sectional view taken on a plane indicated by the dotted line 3 in Fig. 2 and looking downward in the 45 direction of the arrow at said line.

Fig. 6 is a fragmentary side elevation illustrating some of the parts as they appear when viewed from the right-hand side of the machine.

50 The typewriting machine to which my invention is shown as applied corresponds with that disclosed in the aforesaid application of Edwin E. Barney, and reference may be made to said application for a more complete disclosure of said machine, only such

parts of the machine being illustrated herein as are necessary to a proper understanding of my invention. The main frame of the machine comprises side frame parts or plates 1 which are suitably connected together and 60 are surmounted by a top plate comprising sections 4. Above the top plate is arranged a platen 5, diagrammatically illustrated in Fig. 1, and which is mounted on a carriage that is adapted for movement or travel 65 transversely of the machine under the control of suitable mechanism. Printing key levers 6 are connected with and are adapted to actuate printing instrumentalities (not shown) which co-operate with the front or 70 printing face of the platen 5. Each top plate section 4 is cut out or formed with an opening indicated at 25 which is bounded by an upturned edging or flange 26, the top edges of the two flanges being inclined upward and inward toward each other. Said flanges provide housings or cups for ribbon spools 27, each ribbon spool comprising two parallel heads or flanges 28 and a core piece 29, the flanges being provided centrally with 80 holes to fit over the supporting shafts. A ribbon 30 is wound on the ribbon spools and from each is led inward toward the printing point through slotways 31 in the housings 26, the unwound portion of the ribbon being 85 threaded midway between the spools through the slots of a ribbon vibrator or carrier 32, said vibrator normally maintaining in the printing portion of the ribbon below the printing point on the platen but being 90 adapted at each printing operation to rise and interpose the ribbon between the platen and the operated type bar. Each ribbon spool is detachably mounted on a ribbon spool shaft 42 that is supported on a detachable bracket or casting 43. There are two 95 of these brackets or castings arranged one at each side of the machine inside the side plates to which said brackets are secured by pairs of screws 44. The brackets 43 herein illustrated differ from the brackets of the aforesaid Barney application, Sr. No. 456,907, in that they are symmetrical to a vertical line or axis passing midway between the attaching screws 44, as will be clear 100 from an inspection of Fig. 6. The advantage of this symmetrical construction over the prior construction is that the brackets herein are interchangeable; that is, the bracket shown at the left may be applied to 110

the right-hand side of the machine, and the right-hand bracket may be applied to the left-hand side of the machine without interfering with the proper functioning of the ribbon mechanism, the brackets being exactly alike and the parts being mounted on them in identically the same way. On the other hand, with asymmetrical brackets, as in the prior construction, it is always necessary to apply the brackets at the sides of the machine for which they were intended, the left-hand bracket not being adapted to the right-hand side of the machine, and the right-hand bracket not being adapted to the left-hand side of the machine. Each of the present interchangeable brackets 43 comprises an inclined body portion 46 and projections 47 and 48, the upper projections being formed with bosses 49 perforated to provide bearing openings for the associate ribbon spool shafts 42. The lower portion 42^a of the shaft 42, which portion co-operates with the bearing opening in the boss 49, is of lesser diameter than the upper portion and is formed with a shallow circumferential groove 42^b which receives the pointed or inner end of a headed screw 42^c that is threaded into the projection 47 from the side (Fig. 5). The length of said screw is such that when it is fully screwed in, its inner end while it will enter to some extent the groove or depression 42^b it will not contact with the bottom of said groove. The construction is such, in other words, that while the spool shaft may turn freely in its bearing it cannot be displaced endwise or withdrawn from said bearing until the retaining screw 42^c is unscrewed to an extent sufficient to clear the groove 42^b. When the screw is thus withdrawn, however, the shaft 42 and the parts mounted or supported thereon may readily be withdrawn or detached. Said parts include for each shaft the associate ribbon spool itself, said spool being detachably secured to the shaft by devices comprising a latch or lever 54. Said latch is arranged in a slot or cutaway indicated at 55, the pivot 56 of said latch bridging said slot. The upper portion of the slot passes completely through the head of the shaft and receives lugs 28^a projecting inward from the upper flange of the ribbon spool, the lower end of the latch 54 co-operating with the lower flange of the ribbon spool to prevent upward displacement of the spool relatively to the shaft. The latch is maintained in operative position by a coiled spring 57 acting against it below its pivot. Attached to the spool shaft 42 below the ribbon spool is a circular support or plate 58 secured to the top face whereof is a ribbon spring of novel construction. Said spring comprises a body portion or main arm 59, the end of which is riveted or otherwise secured to the support 58 near its per-

iphery, the opposite end of the body portion being formed with an eye or annulus 60 which loosely embraces the associate ribbon spool shaft. Projecting from the eye 60 diametrically opposite from the arm 59 is an angular extension or tongue 59^a which is off-set downward and terminates in an outward projecting tip 59^b. The tendency of the spring 59, 60 is to stand away from the supporting disk 58 as illustrated in Fig. 2, but when the ribbon spool is in place this tendency is overcome and the spring is held substantially flat against the support, the spring at this time maintaining the lower flange of the spool pressed up into engagement with the lower end of the latch 54. When said latch is operated to release the ribbon spool the spring 59, 60 becomes effective to lift the spool far enough to carry its upper flange above the top edge of the cup or housing 26, thus enabling the operator readily to grasp the spool and remove it from the cup. It will be observed from Figs. 2 and 3 that the eye portion 60 of the spring is slightly bent at diametrically opposite sides on a line 70 passing through the axis of the shaft, as indicated at 60^a. The bends or edges 60^a being slightly above the upper plane face of the spring will cause contactive action of the spring against the spool along said edges so 75 that the lifting force of the spring will act substantially axially of the spool shaft, this construction tending to promote an even lifting or raising of the ribbon spool from its seat or bed. The lifting spring 59, 60 has also an additional function to be hereinafter referred to. The plate 58 is perforated to fit over the hub 62 of a small gear wheel 63 comprised in the ribbon feeding mechanism, said gear wheel being secured to 80 the spool shaft by a pin 64 which passes through the hub 62 at one side of the opening therein, and so as to cut into the face of the spool shaft at one side of its axis as will be clear from Fig. 2. This permits the slot 85 55 to be extended downward below the plane of the cross pin without cutting the latter. The slot, as will be observed from Fig. 2, is thus left clear and unobstructed through the full width of the gear wheel 63 and its 90 hub 62, thus providing a longer slot than in the prior construction. This increased length of the slot is made use of in the mounting of certain elements in the train of improved novel reversing devices to be hereinafter described. The upper end of the hub 62 may be grooved to receive the perforated plate 58, the portion of the hub above the groove being spread or upset to fix the plate in place. The gear wheel 63 constantly 95 intermeshes with a pinion 66 fixed to the upper end of a feed shaft 67, said shaft bearing near its upper end in the projection 47 of the associate bracket 43. The feed shaft extends downward and near its lower 100

end bears in the projection 48, which is slotted as indicated at 68 to receive a collar 69 fixed to the shaft to prevent endwise displacement thereof but without interfering with its rotation. Each shaft 67 carries at its lower end a beveled pinion 71 which is adapted to co-operate with one of a pair of beveled driving pinions 73 mounted on a transverse ribbon driving or power shaft 74, said shaft being horizontally disposed and mounted in the lower part of the main frame. Associated with each driving pinion 73 is a worm 76 comprised in the ribbon reversing mechanism. Said driving pinions 15 are so disposed along the shaft 74 that they are adapted for alternative engagement with their associate beveled pinions 71 so that when one of said driving pinions is operative the other pinion will be inoperative, as shown in Fig. 1. As appears therefrom, the turning movement of the driving shaft 74 will be transmitted to the left-hand ribbon spool, causing the ribbon to wind thereon, corresponding amounts being drawn on or 20 unwound from the right-hand spool. In order to reverse the feeding of the ribbon the shaft 74 is moved endwise toward the right to cause disconnection of the left-hand driving pinion and a connection or operative engagement of the right-hand driving pinion with the associate train of spool turning devices. The ribbon driving shaft 74 is automatically turned to feed the ribbon by impulses communicated by the printing key 25 levers 6 through a train of connections including a shaft 81, arranged parallel with and below the shaft 74, said shaft 81 being supported on stationary brackets 82 which receive bushings 84 in which the end portions of the shaft 81 bear. A collar or hub 87, pinned to the outwardly projecting right-hand end portion of the shaft 81, has a forwardly projecting crank arm 88. Arranged on the shaft 81 near its ends are a 30 pair of parallel crank arms, the right-hand one of said crank arms being shown in Fig. 1 and numbered 89, said crank arms being provided with hubs 90 that fit over the shaft 81 and are fixed thereto. The crank arms 35 89 are connected at their free ends by a cross bar 92 which is adapted to be operated from the printing key levers, said cross bar serving as a universal bar both for the ribbon feeding mechanism and also for the ribbon 40 vibrating mechanism. It will be understood that when a key lever is depressed, the universal bar 92 will be swung rearward, communicating a limited extent of rotary movement to the shaft 81 and swinging upward 45 the crank arm 88 on said shaft. Said crank arm has pivoted to it a pawl arm 93 provided with a laterally extending tooth 93^a that co-operates with the teeth of a ratchet wheel 104 fixed to the ribbon driving shaft 50 74 near its right-hand end, said ratchet wheel being turned to a limited extent by the action of the pawl, this movement being participated in by the ribbon driving shaft 74 and its driving pinions 73. The engaged one of the pinions, the left-hand pinion in 55 Fig. 1, will transmit such movement to its associate beveled pinion 71 which in turn will effect a rotation of the upstanding feed shaft 67, causing the pinions carried by said shaft at its upper end to turn the associate gear wheel 63 and the counter or spool shaft 42 together with the ribbon spool mounted thereon. Said spool as it turns winds on it a portion of the ribbon and advances the 60 unwound portion of the ribbon leftwardly, 80 altering to some extent the printing portion of the ribbon which is to receive the next type impression. It will be understood that at each printing operation an impulse will be communicated to the train of ribbon feeding mechanism in the manner described, the result being that the ribbon will be automatically fed or advanced longitudinally from one ribbon spool to the other, and that this automatic feeding or advance may be 85 continued for the full length of the ribbon. 90

The automatic reversing mechanism is effective to move the ribbon driving shaft 74 longitudinally back and forth, the shaft being held in predetermined longitudinal positions by a detent device comprising a collar 162 fixed to the shaft, said collar being provided with circumferential grooves 165 and 166. Co-operative with said collar is a coiled spring or detent spring 168 housed 95 in a two-part box 169, 170. The automatic ribbon reversing mechanism proper, wherein my present invention more particularly resides, is controlled by plies of the ribbon, said mechanism comprising a reversing device or member designated as a whole by the numeral 200. Said device is preferably formed of a single piece of sheet metal and comprises an upright or ribbon engaging portion 201 having parallel angularly disposed sides 202 which extend downward below the bottom edge of the central part 201 and are perforated to receive the pivotal support of said member 200. One of the sides 202 is formed with a horizontally disposed inward extension 203 which is curved or off-set toward the rear as viewed in Fig. 3, thus bringing the end portion of the arm or extension 203 in a plane about central of the device 200. Said device is received in an opening or cutout indicated at 204 in the plate 58, the sides of said opening 204 being provided with downward extensions or ears 205 which receive a pivot pin 206, said pivot pin passing through the 100 perforated lower ends of the sides 202 and providing a pivotal support for the member 200. The extension or arm 203 of said member projects inward past the axis of the spool shaft 42 through a slot or cutout in 105 110

115

120

125

130

dicated at 207 formed in the hub 62 of the gear wheel 63. The cutout 207 extends downward into the top of the gear wheel 63 and connects with the lower end of the slot 5 way 55 in the ribbon spool shaft, thus providing a continuous opening, affording freedom of motion for the arm 203 about the pivotal center 206. As clearly appears from Figs. 2 and 3 the tongue 59^a extends between the side walls 202 of the member 200 and the tip 59^b underlies the bottom edge of the body or central portion 201 of said member. Owing to the inherent tendency of the spring device 59, 60 to rise, the tip 59^b will press upward against the bottom edge of the portion 201 when the ribbon spool is removed and will maintain the device 200 in the position illustrated in Fig. 2. Ordinarily, however, the spring device 59, 60 is held out of commission by the bottom flange of the ribbon spool, and the upright portion 201, 202 of the device 200 is maintained upright by the inner ply or plies of the ribbon 30 as illustrated at the left-hand side in Fig. 1. In this position the upright ribbon engaging portion 201 of the device 200 is maintained within the core 29 of the ribbon spool, said core being provided with a slot indicated at 29^a to afford play or swing of said portion 201 in and out about its pivotal axis 206. When there are one or more plies of the ribbon wound on the spool core 29 the inner ply bridging the slot 29^a will co-operate with the upright portion or arm 201 of the device or lever 200 and hold it within the slot, thereby maintaining the extension or arm 203 in the position illustrated at the left-hand side of Fig. 1, and also in Fig. 2. Said arm 203 co-operates with the head 208 of a slide pin 209 which is received in a bore or perforation formed axially in the lower portion 42^a of the shaft 42. The head 208 of the slide pin underlies the arm 203 and has a limited play in the lower portion 40 of the slot 55, while the pin proper 209 has a limited sliding movement in the bore of the ribbon spool shaft. The lower end of said pin projects below the lower end portion of the shaft 42^a and is rounded at its tip, the rounded tip being adapted to co-operate with a reversing device or gravity operated lever member designated as a whole by the numeral 210. Said lever member 210 is preferably formed of a single piece of sheet metal and comprises a central or pivotal portion 211 extended at 212 to provide a contact arm, the sides of the pivotal portion being bent at right angles to provide parallel bearing ears 213, one of said ears being extended and spread in a general triangular or plate-like shape to form the gravity arm 214 of the lever member 210. Said gravity arm is off-set or bent so that its free portion lies substantially in the central plane of the member 210. The ears 213

loosely embrace a lug 47^a formed on and extending from the lower side of the projection 47, said ears being perforated to receive a pivot pin 215 which bears in an opening in the lug 47^a, said pivot pin being headed at its ends to prevent accidental displacement. When thus pivotally supported the arm 212 of the member 210 underlies and co-operates with the pointed tip of the pin 209. The gravity arm 214 is perforated near its outer end to receive the upper offset or hook portion 216 of a reversing pin 217, said pin being thus pivotally supported on the gravity arm and dependent therefrom, the lower end portion of said pin being guided in a hole formed in the projection 48 of the bracket 43. The lower end or tip of the pin 217 is beveled or pointed as indicated at 218 and is adapted to co-operate with the associate worm 76, the pointed end 218 being normally suspended, however, above the position at which it may engage with said worm. It will be understood that there are two trains of reversing devices, each comprising a pivoted device 200 which in effect operates as a bell crank lever, a headed slide pin 208, 209, a gravity operated lever 210 and a reversing pin 217. The co-operating worms 76 are so disposed along the ribbon driving shaft 74 that only one of them at a time is positioned for engagement with its associate reversing pin 217 as will be understood from Fig. 1. Normally, the pivoted reversing device or bell crank 200 is maintained by the ribbon plies in the position illustrated at the left-hand side of Fig. 1, in constant opposition to the force of gravity exerted chiefly through the lever 210. In said position the arm 203 of said device or member 200 acting against the head 208 of the slide pin will maintain said head in its lowermost position in contact with the top of the gear wheel 63. When the slide pin is thus held its rounded tip will hold down the arm 212 of the member 210 with the result that the gravity arm 214 is maintained in its uppermost position, holding the suspended pin 217 up above the operated field of the associated worm 76. It will be understood that owing to the weight of the lever arm 214 the tendency of the arm 212 is constantly to rise and lift the pin 209, the head of said pin pressing upward against the arm 203 and tending to maintain the upright portion 201 pressed outward against the ribbon ply bridging the slot 29^a. When the ribbon has been wholly unwound from the ribbon spool uncovering the slot 29^a, the upright portion 201 of the bell crank will swing outward through the slot 29^a, the arm 203 will swing upward, and the pin 209 will rise, thus freeing the lever 210, all under the impulse of the force of gravity, acting chiefly through the lever member 210, the weight arm 214 whereof will be 130

free to swing downward permitting the reverse-pin 217 to slide down into working position. The position then occupied by the train of reversing devices is that illustrated 5 at the right-hand side of Fig. 1. After the lowering of the pin 217 and its engagement with the associate worm 76 further rotary movement communicated to the driving shaft 74 through actuations of the printing 10 keys will cause said shaft as it is rotated to be wormed along or moved longitudinally to effect the disconnection of one ribbon spool from the driving shaft and the operative engagement or connection of the other 15 spool therewith so that subsequent impulses from the printing keys will be transmitted to the newly connected spool, causing it to turn to wind the ribbon thereon, corresponding amounts being drawn from the loose or 20 disconnected spool. When the latter spool has thus been emptied of ribbon the reversing mechanism again will become automatically effective in the manner described. It will be understood that the spring detent 25 mechanism comprising the collar 162 and the detent 168 is effective not only to maintain the driving shaft in predetermined longitudinal positions but will also assist by reason of the cam action of the sides of 30 the grooves in the collar 162 to complete the reversing movement of the driving shaft.

From what has been said it will be plain that the spring 59, 60 has a double function, viz., not only does it lift the ribbon spool 35 when the spool latch 54 is operated but the tongue 59^a, 59^b, co-operating with the member 200, will hold it against swinging outward and in substantially the position in which it is normally maintained by the ribbon 40 plies. The bottom edge of the portion 201 serves as a stop to limit the upward movement of the lifting spring away from the plate 58. The body or upright portion 201, 202 is shaped so that the corners are 45 smooth and rounded and its top or tip is curved inward as illustrated, all to facilitate and promote co-operation with the ribbon. From Figs. 1 and 2 it will be apparent that the inwardly curved tip of the upright portion 50 of the member 200 is well within the core of the spool when the member 200 is normally maintained so that when a ribbon spool is replaced there is sufficient margin of safety to insure that said tip shall pass 55 easily inside the inner ribbon plies, permitting the unobstructed restoration or replacing of said ribbon spool.

It will be observed that by my present invention the ribbon reversing mechanism 60 has been greatly simplified, a large number of parts employed in the prior construction having been rendered unnecessary and eliminated. My improved ribbon reversing mechanism is readily assembled and has 65 been found highly efficient in the practical

operation of the machine, responding promptly as soon as the parts are released by the ribbon plies and acting without subjecting the ribbon itself to any undue strain or pull.

Various changes may be made without departing from my invention.

What I claim as new and desire to secure by Letters Patent, is,

1. In ribbon reversing mechanism for typewriting machines, the combination of 75 a ribbon spool, a reversing device controlled by the ribbon on said spool, a gravity operated lever, a slide pin connecting said lever with said device, a reversing pin suspended from said lever, a ribbon driving shaft, and a worm connected thereto, said reversing pin co-operating with said worm.

2. In ribbon reversing mechanism for typewriting machines, the combination of 85 a ribbon spool, a reversing device controlled by the ribbon on said spool, a gravity operated lever, a slide pin connecting the light arm of said lever with said device, a reversing pin pivotally suspended from the 90 heavier arm of said lever, a co-operating worm, and a ribbon driving shaft with which said worm is connected.

3. In ribbon reversing mechanism for typewriting machines, the combination of 95 a ribbon spool, a pair of gravity operated levers, one controlled by the ribbon on said spool, connections between said levers, a reversing pin supported by one of said levers, a ribbon driving shaft, and a device 100 on said shaft co-operative with said reversing pin.

4. In ribbon reversing mechanism for typewriting machines, the combination of a 105 ribbon spool, a pair of gravity operated levers, one controlled by the ribbon on said spool, a slide pin connecting said levers, a reversing pin supported by one of said levers, a ribbon driving shaft, and a device on 110 said shaft co-operative with said reversing pin.

5. In a reversing mechanism for the ribbon spools of typewriting machines, the combination of a ribbon spool shaft, a slide pin, 115 said shaft providing a bearing for said pin, a pair of gravity operated levers connected by said pin, one of said levers being controlled by the ribbon on said spool, a reversing pin supported by one of said levers, a ribbon driving shaft, and a device on said shaft co-operative with said reversing pin.

6. In reversing mechanism for the ribbon spools of typewriting machines, the combination of a ribbon spool shaft, a slide pin, 125 said shaft providing a bearing for said pin, a pair of gravity operated levers connected by said pin, one of said levers being controlled by the ribbon on said spool, and having an arm extending through a slot in the spool shaft transversely across the axis 130

thereof, said arm contacting with said slide pin, the other of said levers having a plate-like arm; a reversing pin pivoted to said plate-like arm; and an element on which 5 said pin acts.

7. In ribbon reversing mechanism for typewriting machines, the combination of a ribbon spool; a pivoted reversing device controlled by the ribbon wound on said 10 spool; and gravity operated devices constantly opposing the control of said pivoted device by said ribbon, said gravity operated devices comprising a lever, a slide pin between said lever and said pivoted device, 15 and a reversing pin supported by said lever.

8. In ribbon reversing mechanism for typewriting machines, the combination of a pair of ribbon spools, pivoted reversing devices associated with said spools and controlled by the ribbon wound thereon, and trains of devices constantly opposing the 20 control of said pivoted devices by said ribbon, said trains of devices each comprising a gravity operated lever connected with its 25 associate pivoted device.

9. In a typewriting machine, the combination of a ribbon driving shaft; worms thereon; a pair of ribbon spools; pivoted reversing devices associated with said spools 30 and controlled by the ribbon wound thereon; and trains of gravity operated devices constantly opposing the control of said pivoted devices by said ribbon, said trains of 35 devices each comprising a lever, a slide pin between said lever and said pivoted device, and a reversing pin pivotally suspended from said lever in position to co-operate with one of said worms.

10. In a typewriting machine, the combination of a ribbon driving shaft; worms thereon; a pair of ribbon spools; pivoted reversing devices associated with said spools and controlled by the ribbon wound thereon; trains of gravity operated devices 45 constantly opposing the control of said pivoted devices by said ribbon, said trains of devices each comprising a lever, a slide pin between said lever and said pivoted device, and a reversing pin pivotally suspended from said lever in position to co-operate with one of said worms; and separate trains of ribbon feeding devices for connecting said spools with said driving shaft.

50 11. In a typewriting machine, the combination of a ribbon spool shaft, ribbon spools thereon, latching devices for said spools,

reversing devices associated with said spools, and spring means for controlling said reversing devices when said spools are detached and also for assisting such detachment, said spring means comprising for each spool a spring arm provided with an annulus loosely embracing the associate shaft and co-operating with the ribbon 60 spool in a direction axially of the shaft.

65 12. In a typewriting machine, the combination of a ribbon spool shaft, ribbon spools thereon, latching devices for said spools, reversing devices one associated with each 70 of said spools, and spring means for controlling said reversing devices when said spools are detached and also for assisting such detachment, said spring means comprising for each spool a spring arm provided with an annulus surrounding the associate shaft and co-operating with the ribbon 75 spool in a direction axially of the shaft, said annulus having a radially projecting tongue contactive with the associate reversing 80 device.

85 13. In ribbon mechanism for typewriting machines, the combination of a pair of unitary structures comprising two brackets detachably secured to the frame of the machine, one at its left-hand side and one at its right-hand side, and ribbon feeding and reversing devices including a spool or carrier mounted on each bracket, said brackets being interchangeable so that they may be 90 removed from and secured at either side of the frame without interfering with the proper operation of the ribbon feeding and reversing devices or disturbing the spools.

95 14. In ribbon mechanism for typewriting machines, the combination of a pair of unitary structures comprising two brackets, and ribbon feeding and reversing devices mounted on each bracket, and securing screws for each bracket, said securing screws 100 being threaded into the bracket symmetrically to its axis and detachably securing the bracket to the frame of the machine at one side thereof, said brackets being interchangeable so that each may be screwed to 105 either side of the machine frame.

Signed at the borough of Manhattan, city of New York, in the county of New York and State of New York, this 8th day of April, A. D. 1921.

JOSEPH PHELPS.
